UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

DESIGN FOR A CRIMPED, CRAPED, OR CRINKLED PAPER OR FABRIC.

56,819.

Specification for Design.

Patented Dec. 28, 1920.

Application filed July 24, 1920. Serial No. 398,822. Term of patent 14 years.

To all whom it may concern:

Be it known that I, WILLIAM A. LORENZ, a citizen of the United States, residing at Hartford, in the county of Hartford and State of Connecticut, have invented a new, original, and ornamental Design for Crimped, Craped, or Crinkled Paper or Fabric, of which the following is a specification, reference being had to the accompanying drawing, forming part thereof.

The figure is a face view of a sheet of paper or fabric, showing my new design.

I claim:

The ornamental design for crimped, craped or crinkled paper or fabric, as shown.

WILLIAM A. LORENZ.

Witnesses:

E. F. ANDREWS,
PHOEBE BUNKER LORENZ.
